Primary Examiner — Kelley A Donnelly

(57) **CLAIM**

The ornamental design for a panel grid framework, as shown and described.

DESCRIPTION

1. Panel grid framework
  2. Panel grid framework
  3. Panel grid framework
- 1.1** : Perspective
1.2 : Top
1.3 : Left
1.4 : Front
2.1 : Perspective
2.2 : Top
2.3 : Left
2.4 : Front
3.1 : Perspective
3.2 : Top
3.3 : Left
3.4 : Front

Title: a panel grid; Use: for storing storage containers; Essential features: positional arrangement of grid members in the panel grid; Figure that best shows the design: perspective view; The right side view is identical to the left side view; The rear side view is identical to the front side view.

1 Claim, 12 Drawing Sheets
